HONING MACHINE AND SIZING MECHANISM THEREFOR

Maurice J. Gross, Rockford, Ill., assignor to Barnes Drill Co., Rockford, Ill., a corporation of Illinois

Application August 14, 1953, Serial No. 374,201

9 Claims. (Cl. 51—34)

This invention relates to honing machines of the type in which a hollow plug for sensing the attainment of a desired diameter of the work bore is mounted on the honing tool head and surrounds the tool spindle so as to come into feeling engagement with the work bore during each reciprocation and enters the bore when the desired diameter has been reached.

The general object is to provide, in a hone assembly of the above character, a sizing plug of adjustable diameter which may be changed in size by the simple manipulation of a novel adjusting member.

A more detailed object is to effect the size adjustment through the intermediary of a wedge member surrounding the tool spindle and movable axially of the latter to expand and contract the gaging surface of the sizing plug.

A further object is to join the sizing plug and the hollow adjusting member by a novel threaded coupling through which the adjustment may be effected simply by turning the adjusting member in one direction or the other.

The invention also resides in the novel construction and arrangement by which the adjusting member limits the collapse of the plug and is accessible for adjustment without disassembly of the honing tool.

Other objects and advantages of the invention will become apparent from the following detailed description taken in connection with the accompanying drawings, in which

Figure 1 is a fragmentary front elevational view of a part of a honing machine equipped with the novel sizing plug of the present invention.

Fig. 2 is an enlarged fragmentary sectional view taken in the plane of the spindle and showing the parts in feeling position.

Fig. 3 is an end view of the gage and the adjusting member.

Fig. 4 is a perspective view of the adjusting member.

Fig. 5 is a sectional view similar to Fig. 2 showing a modification of the invention.

Fig. 6 is a fragmentary longitudinal sectional view of a honing machine embodying another modified form of the invention.

Fig. 7 is a perspective view of the adjusting member used in the form shown in Fig. 6.

The invention is shown in the drawings for purposes of illustration incorporated in a so-called vertical machine in which a workpiece 10 is suitably clamped on a horizontal support 11 to locate its bore 12 in position to be honed in a succession of vertical reciprocations of a honing tool 13. The latter is carried on the lower end of an elongated tubular spindle 14 projecting downwardly from and journaled for rotation on a head 15 which is slidably vertically and accurately guided along laterally spaced rods 16 mounted in the usual way on a column 17 upstanding from the machine base.

Suitable power actuators and controls well known in the art reciprocate the head 15, turn the spindle 14, and expand and collapse the hone 13 to effect each honing

2

cycle which includes entry of the collapsed hone into the work bore 12, expansion of the stones 18 under pressure against the bore wall, simultaneous reciprocation and rotation of the hone within the bore until the latter is enlarged to a predetermined size, collapse of the hone, and withdrawal of the tool out of the finished bore. Expansion and collapse of the honing stones 18 is usually effected by cams within the hone body 19 actuated by a rod 20 extending up through the hollow spindle 14 to a power actuator 21.

To determine when the bore 12 has been honed to the desired diameter, a hollow gaging element 22 surrounding the drive spindle is mounted on the head 15 for reciprocation with the latter so as to come into feeling engagement with the workpiece 10 during each down stroke and enter the bore 12 when the desired diameter is reached. The gaging element is in the form of a ring integral with the lower end of a sleeve 26 through which the spindle projects loosely thus allowing for free lateral floating transaxially of the gaging element.

In the form illustrated in Figs. 1 through 4, the external surface 25 of the gage ring 22 is finished accurately and constitutes a part of a sphere so that the ring will, irrespective of the angular position of its axis, enter the bore 12 under spring loading when the bore has been enlarged to the desired size. Transaxial floating of the ring is obtained by supporting the sleeve 26 at its upper end for universal swiveling about a center substantially coincident with the spindle axis. The swivel joint is formed in part 25 by a spherical enlargement or ball 27 whose external surface 28 is seated in a mating surface 29 on a flange 30 through which the sleeve 26 projects to expose the gage 22 to the work. The flange 30 is on the end of a tube 31 somewhat larger than the sleeve and having at its other end an external flange 32 secured as by screws 33 to a bracket 34. The latter is slideable along stationary guides 35 paralleling the head guides 16 and is connected as by bolts 36 to the head 15 for movement with the latter.

Cooperating with the surface 29 to complete the ball joint is a second internal surface 37 disposed above the ball 27 and formed on the lower end of a sleeve 38 whose lower flange end is guided in the cylindrical bore 39 of the tube 31. To urge the sleeve 38 endwise toward the ball 27, a spring 40 coiled around the sleeve acts in compression between a flange 41 and an opposed abutment 42 on the tube 31 near the upper end thereof.

During the honing operation, the gage sleeve 26 moves up and down with the head. Near the end of each down stroke, the gaging surface 25 partially enters the bore 12 and comes against the end of the wall thereof as shown in Fig. 1. When the bore is undersize, the gage is blocked against further movement so that, in the continued short movement of the head to complete the down stroke, the lower surface 29 of the ball joint moves away from the ball 27. If the sleeve 26 is out of alignment with the bore, it swivels about the center of the bore 27 and automatically becomes centered in the bore. When the bore finally reaches the desired diameter, the spherical gage 22 enters fully into the bore. As a result, the gage sleeve 26 and the sleeve 38 continues down with the head during the final portion of the stroke. This movement, which indicates that the bore is to size, is sensed by a switch 48 (Fig. 5) that is contacted by an arm 45 projecting radially outwardly from the flange 41 on the sleeve 38 through a slot 44 in the tube 31. The switch may be utilized in a manner well known in the art to cause collapse and withdrawal of the hone.

According to the invention, the gaging element 22 is constructed in a novel manner to be adjustable in diameter and thus is adapted for use in honing different size bores. Such adjustment is achieved without materially

increasing the space required by the gaging element and without interfering with either the normal honing action of the tool 13 or the transaxial floating of the gage. To these ends, the gaging element is made radially expandible and is adjusted in size by the simple manipulation of a novel adjusting member 60 which preferably is accessible from the exterior of the honing machine so that the adjustment may be made without disassembling any of the parts. Although the gaging element is expandible, its size is rigidly maintained by the adjusting member so that the gage accurately determines when the bore 12 has attained the desired diameter.

To make the gaging element 22 expandible, the lower or gage end of the sleeve 26 is divided into a plurality of angularly spaced parts 61 which are moved radially by the adjusting member 60 to change the diameter of the gaging surface 25. These parts 61 are integrally joined to preserve the one-piece construction of the gaging element and are resilient so that they are flexed to change the size of the gage. Such flexing is obtained by forming the adjusting member 60 as a hollow wedge encircling the spindle 14 and engaging the gage parts 61 which thus are moved radially when the wedge is shifted axially. Preferably, the wedge 60 acts against the inside of the flexible parts 61 and serves as a rigid backing for the latter to prevent the gage from collapsing when entering the bore 12.

Axial shifting of the wedge 60 to flex the gage parts 61 is obtained through the medium of a coupling 62 which connects the wedge and the parts. This coupling causes the wedge to move accurately along the axis of the gaging element 22 and thus insures that the parts 61 are moved radially equal amounts to obtain a uniform change in the size of the gaging surface 25. Herein, the coupling 62 is a threaded connection joining the wedge and the sleeve 26 so that the wedge is shifted axially when turned in opposite directions.

In the present instance, advantage is taken of the fact that the sleeve 26 is supported only at its upper end to form the radially movable parts 61 by slotting the sleeve longitudinally from the lower end of the sleeve up to a point a substantial distance above the gaging surface 25, the slots 63 terminating in small holes 64. The portions of the sleeve between adjacent slots are, in effect, axially projecting resilient fingers which may be flexed outwardly to enlarge the diameter of the gage surface without changing the effective contour of the gage and which thus constitute the radially movable parts 61. At the lower end of the sleeve 26, the internal surfaces 65 of the fingers 61 are flared outwardly and these tapered surfaces are engaged by the wedge 60 to flex the fingers outwardly as the wedge is moved up along the spindle 14.

Preferably the wedge 60 is a ring with an outer conical surface 66 mating with the internal tapered surfaces 65 on the fingers 61. The threaded coupling 62 between the ring 60 and the sleeve 26 may, as illustrated in Figs. 1 through 4, be made to occupy the same axial space as the wedge by cutting threads directly on the tapered wedge and finger surfaces 65 and 66. At its lower end, the wedge ring projects below the gage sleeve and has a flange 67 in which radial slots 68 are cut to receive a suitable spanner wrench for turning the ring to shift the latter axially. With the end of the ring exposed in this manner, the adjustment of the ring and hence of the gaging surface diameter is readily effected from the exterior of the honing machine.

By turning the wedge ring 60 to move the latter up into the sleeve 26, the fingers 61 are flexed and the diameter of the gaging surface 25 is increased progressively. Turning the ring in the opposite direction results in the wedge shifting down relative to the sleeve and permits the fingers to contract reducing the gaging surface diameter. The proper size of the surface 25 may be determined easily by means of a suitable micrometer or a master gage.

Instead of forming the threaded coupling 62 along the

5 same portions of the sleeve 26 and the wedge ring 60 occupied by the tapered surfaces 65 and 66, the coupling may be separated from these surfaces as shown in Fig. 5. In this case, a smooth wedge surface 66^a on the ring 60^a 10 engages similar surfaces 65^a on the insides of the gage fingers 61^a and effect the expansion of the gage when the ring is shifted axially. The threaded coupling 62^a comprises a thread cut on a cylindrical extension 69 of the wedge ring above the wedge surface 66^a and mating with a thread in an enlargement 70 of the sleeve bore 24. In other respects, this arrangement is the same as illustrated in Figs. 1 through 4.

15 The invention also is applicable to a gage which has a cylindrical rather than a spherical gaging surface and which is mounted for bodily lateral shifting instead of universal swiveling. In the modification shown in Figs. 6 and 7 for example, the gaging surface 25^b is formed on the outside of a cylindrical sleeve or ring 22^b abutting against the lower flanged end of a sleeve 38^b which slides axially in the tube 31^b. The inner surface 65^b of the gage ring 22^b is flared downwardly and mates with the conical surface 66^b of the wedge ring 60^b. A cylindrical extension 69^b of the latter above the conical surface 66^b is threaded into the sleeve 38^b to form the threaded coupling 62^b and permit axial adjustment of the wedge ring. Thus, in this case, the wedge ring serves the additional function of holding the gage ring 22^b in place against the sleeve 38^b.

20 To permit lateral floating of the gage 22^b, the flange 41^b on the lower end of the sleeve 38^b is smaller, for example .020-.030 of an inch, than the bore 39^b of the tube 31^b. At its lower end, the gage ring is tapered as indicated at 71 and thus converges downwardly to a diameter smaller than the final work bore 12 by an amount slightly greater than the permissible lateral float of the ring. As a result, the gage ring shifts laterally and becomes centered with the work bore when the tapered end 71 of the ring encounters the work.

25 The spring 40^b helically coiled around the sleeve 38^b acts in compression on a washer 72 bearing against the flange 41^b and yieldably urges the sleeve downwardly toward the position shown in Fig. 6 limited by a washer 73 and the inturned flange 30^b on the lower end of the tube 31^b against which washer the sleeve flange seats. As in the case of the swiveled gage, the spring 40^b urges the gage 22^b into contact with the workpiece and permits the gage to move up into the tube 31^b when the work bore 12 is undersize.

30 The radially movable parts 61^b which are flexed to expand the gage ring 22^b are defined by slots 63^b extending longitudinally of the ring. The slots extend throughout the major portion of the length of the ring and alternate slots are cut from opposite ends of the ring. With this arrangement of the slots, the two ends of the ring expand equally when the wedge 60^b is advanced into the sleeve 38^b and thus the gage ring 22^b retains its cylindrical shape in all positions of adjustment.

35 It will be observed that, with the present invention, the gaging surface is readily adjustable in diameter and thus a single gage may be used in honing bores of various diameters. Whether a spherical or cylindrical gaging surface is used, the adjustment is effected by a simple turning of the wedge 60 to thread the latter into or out of the gage ring 22. This adjustment may be made easily from the exterior of the honing machine without disassembling any of the parts. By arranging the wedge to expand the gaging surface from the inside of the gage sleeve, the latter is made rigid so that it does not collapse upon entering the work bore.

40 I claim as my invention:

45 1. In a honing machine, the combination of, a reciprocable head, a rotary spindle projecting from said head and carrying a hone for operating in a work bore, a gaging sleeve loosely encircling and extending along said spindle and mounted on said head for movement axially

of the spindle and also for lateral shifting relative thereto in a transaxial plane, a feeler on the end of said sleeve adjacent the hone having an external spherical surface adapted to enter the bore when the latter is honed to the proper size, the spherical end portion of said sleeve remaining of fixed diameter in said plane for all lateral positions of the sleeve and being slotted longitudinally to form a plurality of flexible fingers angularly spaced around the sleeve, a ring larger than and encircling said spindle and having an external wedge surface engaging the interior of said fingers, and a threaded connection between said ring and said sleeve and operable when the ring is turned in opposite directions to shift the ring axially and permit flexing of said fingers thereby to adjust the diameter of said feeler surface.

2. In a honing machine, the combination of, a reciprocable head, a rotary spindle projecting from said head and carrying a hone for operating in a work bore, a sleeve loosely encircling and extending along said spindle, means on said head mounting said sleeve for movement axially of the spindle and also for transaxial movement into a plurality of different positions, a ring supported on the lower end of said sleeve adjacent the hone and having an external gaging surface adapted to enter the bore when the latter is honed to the proper size and having a diameter of fixed length in a transaxial plane in all of said positions, said ring being slotted longitudinally to form a plurality of radially movable parts having smooth internal surfaces tapering longitudinally, a wedge ring larger than and encircling said spindle and having a wedge surface mating with said tapered surfaces, and a cylindrical extension on said wedge ring threaded into a cylindrical portion of the bore of said sleeve and operable when the wedge ring is turned to cause shifting of the ring axially and movement of said parts radially thereby to adjust the diameter of said gaging surface.

3. In a honing machine, the combination of, a reciprocable head, a rotary spindle projecting from said head and carrying a hone for operating in a work bore, a gaging sleeve loosely encircling and extending along said spindle, means on said head supporting said sleeve for axial movement along said spindle and also for lateral shifting relative thereto in a transaxial plane, a plurality of angularly spaced flexible parts projecting axially from the end of said sleeve adjacent said hone, an external feeler surface on the outside of said parts adapted to enter the bore when the latter is honed to the proper size, said surface remaining of fixed diameter in said plane for all lateral positions of the sleeve, an internal thread formed around the interior of said fingers and tapering along the axis of said sleeve, and a tapered ring larger than and encircling said spindle and having an external thread mating with the thread on said fingers whereby the ring when turned in opposite directions causes flexing of the fingers to expand and contract said surface.

4. In a honing machine, the combination of, a reciprocable head, a rotary spindle projecting from said head and carrying a hone for operating in a work bore, and a plug type gage for detecting enlargement of the bore to a predetermined diameter, said gage comprising a tubular sleeve loosely encircling and extending along said spindle and having the end portion adjacent the hone slotted longitudinally to form a plurality of axially projecting flexible fingers angularly spaced around the sleeve, means supporting said sleeve from its other end for axial movement along said spindle and also for lateral shifting relative thereto in a transaxial plane, an external feeler surface extending around said sleeve on the outer sides of said fingers and remaining of fixed diameter in said plane for all lateral positions of the sleeve, an internal surface formed around the interior of said fingers and tapering along the axis of said sleeve, a tapered ring encircling said spindle and mating with said tapered surface, and a threaded connection between said ring and said sleeve and operable when the ring is turned to shift the ring

axially and cause flexing of said fingers thereby to adjust the diameter of said feeler surface.

5. In a machine for honing a work bore, the combination of, a reciprocable tool head, a rotary spindle mounted on said head and carrying a hone for operating in the bore, a gage sleeve surrounding and extending along said spindle and supported on said head for movement axially of the spindle and also for lateral shifting relative thereto in a transaxial plane, the end portion of said sleeve adjacent said hone being slotted and flexible to expand and collapse, an external feeler surface formed on the outside periphery of said sleeve in the slotted end portion thereof to enter the work bore when the latter is honed to the proper size, said feeler surface remaining of fixed diameter in said plane for all lateral positions of the sleeve, a tapered surface formed on the slotted end portion of said sleeve and tapering axially of the sleeve, a ring larger than said spindle and having a tapered surface mating with the surface on said sleeve and operable when the ring is moved axially in opposite directions to expand and contract said slotted end portion and thus vary the diameter of said surface, and a threaded connection between said ring and said sleeve and operable to cause the ring to move axially when turned.

20 6. In a honing machine, the combination of, a head having a rotary spindle projecting therefrom and carrying a honing tool, a tubular gaging ring encircling said spindle and mounted on said head for axial movement along the spindle and also for lateral shifting relative thereto in a transaxial plane, said ring having a plurality of angularly spaced radially movable parts defining an external gaging surface remaining of fixed diameter in said plane for all lateral positions of the ring, a hollow wedge larger than and encircling said spindle and engageable with the interior of said parts, and a threaded coupling connecting said wedge and said ring and operable in response to relative turning of the wedge and the ring in opposite directions to shift the wedge axially and expand and contract said parts thereby to change the diameter of said gaging surface.

25 7. In a honing machine, a head having a rotary spindle projecting therefrom and carrying a honing tool, a hollow gaging element encircling said spindle and mounted on said head for axial movement along the spindle and also for lateral shifting relative thereto in a transaxial plane, said element having a plurality of angularly spaced radially movable parts defining an external gaging surface remaining of fixed diameter in said plane for all lateral positions of said element, a hollow member encircling said spindle and shiftable axially of said element, said member constituting a wedge engaging said parts to expand or contract said surface upon shifting of the member, and a threaded coupling associated with said member and operatively connecting said member and said element to shift the wedge axially in opposite directions in response to relative turning of the parts of said coupling.

30 8. In a honing machine, the combination of, a reciprocable head, a rotary spindle projecting from said head and carrying a hone for operating in a work bore, a hollow gaging element encircling said spindle and mounted for axial movement along the spindle and also for lateral shifting relative thereto in a transaxial plane, said element having a plurality of angularly spaced radially movable parts defining an external gaging surface whose diameter in said plane remains fixed for all lateral positions of said element, a ring encircling said spindle and shiftable axially of said element, said ring having a wedge surface engaging said parts to expand or contract said gaging surface upon shifting of the member, and a coupling joining said ring and said element and operable to effect axial shifting of the ring to vary the size of said gaging surface.

35 9. In a honing machine, the combination of, a rotary spindle carrying a honing tool, a hollow gaging element

encircling the axis of said spindle, means supporting said element for axial movement along said axis and also for lateral shifting relative thereto in a transaxial plane, said element having at one end a plurality of angularly spaced radially movable parts defining an external gaging surface remaining of fixed diameter in said plane for all lateral positions of said element, a member accessible for adjustment from said element end and mounted within said parts for independent shifting along said axis, said member constituting a wedge engaging said parts to expand or contract said surface upon shifting of the member, and a threaded coupling associated with said mem-

ber and operatively connecting said member and said element to shift the wedge axially in opposite directions in response to relative turning of the coupling parts.
